UNITED STATES PATENT OFFICE.

JOSEPH YAVORSKY, OF YOUNGSTOWN, OHIO.

COMBINED COMB AND BRUSH.

Application filed January 31, 1924. Serial No. 689,759.

To all whom it may concern:

Be it known that I, JOSEPH YAVORSKY, a citizen of Czechoslovakia, residing at Youngstown, in the county of Mahoning and State of Ohio, have invented certain new and useful Improvements in Combined Combs and Brushes, of which the following is a specification.

This invention relates to certain new and useful improvements in combined combs and brushes of the type wherein a comb is supported upon the back of a brush permitting selective use of a comb or brush in a single combined implement.

15 The primary object of the invention resides in the provision of a combined comb and brush and the particular manner of supporting the comb upon the brush back whereby the same may be readily removed 20 for purposes of cleaning or replacement and when supported upon the brush back will possess sufficient rigidity for performing the natural functions thereof.

With the above and other objects in view 25 as the nature of the invention is better understood, the same consists of the novel form, combination and arrangement of parts hereinafter more fully described, shown in the accompanying drawings and claimed.

30 In the drawings, wherein like reference characters designate corresponding parts throughout the several views,

Figure 1 is a top plan view of a combined comb and brush constructed in accordance 35 with the present invention,

Figure 2 is a side elevational view of the same,

Figure 3 is a cross sectional view taken on line III—III of Figure 2 showing the removable plate sections for the brush back engaging the opposite sides of the base portion of a comb,

Figure 4 is a cross sectional view taken on line IV—IV of Figure 1 showing the interlocking connection between the removable plate sections that grip the comb,

Figure 5 is a fragmentary top plan view showing by dotted lines, the connecting means between the plate sections,

50 Figure 6 is a cross sectional view taken on line VI—VI of Figure 5 showing the tensioned latch arm carried by one plate engaging a keeper lug carried by the other plate, and

55 Figure 7 is a detail sectional view taken on line VII—VII of Figure 6.

Referring more in detail to the accompanying drawing, there is illustrated a combined comb and brush wherein the brush backing 1 carrying the usual bristles 2 is 60 provided with a handle 3 upon one end thereof. For purposes presently to appear, the brush backing 1 is provided with a transversely extending dove-tail-shaped groove 4 in the upper side thereof opposite 65 the bristles 2.

A pair of back plates 5 and 6 combined to form the general outline of the brush backing 1 are slidably associated with the brush backing transversely thereof, each of the 70 back plates 5 and 6 carrying a depending transversely extending dove-tail-shaped rib 7 that is slidably received in the groove 4 of the brush backing 1. The longitudinal meeting edges of the back plates 5 and 6 are 75 formed with matching recesses 8 that are reduced at opposite ends thereof as at 9 and shown more clearly in Figures 5 and 7. A comb 10 has its base portion disposed in the recess 8 and a felt or other cushion packing 80 strip 11 is interposed between the comb and walls of said recess and extend outwardly through the reduced portions 9 of said recess to be clamped between the back plates 5 and 6. Movement of the back plates toward 85 each other is limited by the rib 12 positioned centrally athwart the dove-tail-shaped groove 4 and projecting upwardly from the bottom wall of said groove to be engaged by the adjacent ends of the ribs 7.

The connection between the back plates 5 and 6 includes the provision of an opening 13 or recess in the under side of the back plate 5 adjacent each end thereof and opening at the straight edge of the plate and having one end of a latch lever 14 secured upon the upper wall of said recess 13 as at 14, the latch lever 14 freely extending through openings provided in the adjacent portions of the cushioning strip 11 and through an opening 15 in the back plate 6, the opening 15 extending completely through the plate 6 and having a relatively wide mouth 16 at its outer end. A latch hook 17 is carried by the upper face of the latch lever 14 and is 100 adapted to be moved into engagement with the keeper lug 18 carried by the plate 19 that is secured to the upper wall of the opening 15. The outer end 14 of the latch lever 14 is adapted to be depressed to disengage 105 the latch hook 17 from the keeper lug 18 at which time the back plates 5 and 6 may be

separated and disengaged from the brush backing 1. The cushioning strips 11 interposed between the back plates and comb provide a substantially resilient mounting for 5 the two back plates and tend to hold the latch lever in engagement with the keeper lug.

While there are herein shown and described the preferred embodiments of the 10 present invention, it is nevertheless to be understood that minor changes may be made therein without departing from the spirit and scope of the invention as claimed.

What is claimed as new is:—

- 15 1. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together.
- 20 2. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together.
- 25 3. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and a cushion strip interposed between the walls of the pocket and the comb.
- 30 4. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together, the plate locking means including a tensioned latch carried by one plate and engaging a keeper lug carried by the other plate.
- 35 5. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and a cushion strip interposed between the walls of the pocket and the comb, the plate locking means including a tensioned latch carried by one plate and engaging a keeper lug carried by the other plate, the connection between the back plates and brush backing including the formation of spaced alined dove-tail-shaped grooves in the upper face of the brush backing and dove-tail-shaped ribs depending from the back plates.
- 40 6. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together, and a cushion strip interposed between the walls of the pocket and the comb, the plate locking means including a tensioned latch carried by one plate and engaging a keeper lug carried by the other plate, the connection between the back plates and brush backing including the formation of spaced alined dove-tail-shaped grooves in the upper face of the brush backing and dove-tail-shaped ribs depending from the back plates.
- 45 7. In a combined comb and brush, a brush backing having bristles projecting from one face thereof, a pair of back plates transversely slidable upon the brush backing and

cut away at their meeting edges to form a comb receiving pocket, a comb in the pocket clamped in position by the back plates, means for locking the back plates together, and a cushion strip interposed between the walls of the pocket and the comb, the plate locking means including a tensioned latch carried by one plate and engaging a keeper lug carried by the other plate.

5. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together, the plate locking means including a tensioned latch carried by one plate and engaging a keeper lug carried by the other plate, the connection between the back plates and brush backing including the formation of spaced alined dove-tail-shaped grooves in the upper face of the brush backing and dove-tail-shaped ribs depending from the back plates.

6. In a combined comb and brush, a brush backing having bristles projecting from one face thereof, a pair of back plates transversely slidable upon the brush backing and cut away at their meeting edges to form a comb receiving pocket, a comb in the pocket clamped in position by the back plates, and means for locking the back plates together, and a cushion strip interposed between the walls of the pocket and the comb, the plate locking means including a tensioned latch carried by one plate and engaging a keeper lug carried by the other plate, the connection between the back plates and brush backing including the formation of spaced alined dove-tail-shaped grooves in the upper face of the brush backing and dove-tail-shaped ribs depending from the back plates.

In testimony whereof I affix my signature.

JOSEPH YAVORSKY.
